COMBINATION LOCK

George T. Hosking, Jamaica Plain, Boston, Mass.

Application November 17, 1947, Serial No. 786,465

2 Claims. (Cl. 70—287)

1

This invention is a combination lock of that type wherein the locking functions of a latch or bolt are controlled by rotatable elements arranged to be adjusted to predetermined relative positions. The invention has particular reference to the structure disclosed in my patent of the United States No. 2,003,650, dated June 4, 1935.

The present development pertains particularly to the manner in which the slide bar, which carries the bolt, cooperates with the rotatable member in both locking and unlocking positions, as well as the manner in which the operating stems coact or interlockingly engage with the rotatable member to either move the latter to locking or unlocking position, as well as to vary the combination for operating the lock.

The present invention provides improved and simplified means for bringing about the same results as those obtained by my aforementioned patent, the present development residing in the simplified construction and arrangement of the improved parts as well as affording a greater variety in the combinations obtainable in the permutation mechanism.

With the foregoing objects in view, together with others which will appear as the description proceeds, the invention resides in the novel construction, combination and arrangement of parts, all as will be described more fully hereinafter, illustrated in the drawing, and particularly pointed out in the claims.

In the drawing—

Fig. 1 is a plan view of a combination lock constructed in accordance with the invention and illustrating the same as applied as a locking means for a trunk, satchel, travelling bag or similar closure.

Fig. 2 is a view similar to Fig. 1 with the cover plate removed and illustrating the lock bolt or slide in retracted position.

Fig. 3 is a view similar to Fig. 2 with the slide projected to locking position.

Fig. 4 is an enlarged longitudinal sectional view taken through the lock casing and showing the parts in the position they will assume with the slide bar or bolt member retracted.

Fig. 5 is a view similar to Fig. 4 and showing the parts in the position they will assume with the slide bar or bolt in projected or locking position.

Fig. 6 is a transverse sectional view taken substantially upon line 6—6 of Fig. 5, and

Fig. 7 is a view similar to Fig. 6 and illustrating a modified form of the invention.

Referring now more particularly to the drawings, 8 represents the housing or casing to contain the lock mechanism, the said housing being preferably of shallow thickness and of rectangular form, open at the top and having flanges 9

2

upon its longitudinal edges to receive the edges of a cover plate 9' to close the casing.

5 Rotatably mounted in the bottom of the casing or housing 8 in the median line thereof and in spaced relationship to one another are rotatable members 10. These members are in fixed position within the casing but are mounted for free rotation therein, as stated. In the present instance, these members take the form of pinions having teeth 11, as shown.

15 Slidably mounted within the casing is a bar or plate 12, the latter being preferably equal to the width of the casing and abutting the sides thereof as shown in Figs. 2, 3, 6 and 7. This plate is mounted so as to slide longitudinally of the housing or casing 8. The plate is provided at one end with an outwardly projecting portion constituting a bolt 13 to extend through an opening 14 in the outer end of the housing when the plate has been moved to projected or locking position. This bolt is to cooperate with a keeper member 15 of the element to be locked for interlocking engagement therewith, as will be readily understood. The slide bar or plate 12 is provided with openings 16 disposed in spaced relationship to one another and of sufficient length and breadth to accommodate the rotatable members 10 and to permit substantial sliding movement of the plate with respect to the said elements or members. Projecting into said openings from the forward ends thereof are lugs 17 of less thickness than the thicknesses of the rotatable members or pinions 10, adapted to slide and to interfit within substantial shallow recesses 18 in the peripheries of the said rotatable members or pinions 10 when the slide bar or plate 12 is in retracted or unlocking position and when the said rotatable pinions 10 are so positioned that the recesses 18 are aligned with the said lugs. The depths of the recesses 18 will be such that when the lugs 17 have extended to their full depth within the said recesses, the plate 12 will have been moved a distance sufficient to withdraw or retract the bolt 13 from locking engagement with its cooperating element 15.

20 Mounted concentrically with each of the rotatable members or pinions 10, are operating shafts 19. In the present instance, these shafts extend within openings centrally provided in the pinions 10, and are disposed transversely of the casing or housing. The shafts extend through the cover plate 9' and are provided on their outer ends with operating knobs 20, and pointers or indicators 21 to travel around dials upon the 25 outer face of the cover plate 9' as shown particularly in Fig. 1. These shafts 19 are capable of rotating independently of the pinions at times and interlock therewith at other times.

30 Rigidly secured to each of the shafts 19 and directly above the pinions 10 are selector plates

22, each of which is provided with a plurality of detents 23 adapted to engage and interlock with the teeth of the pinions 10. An expansion spring 24 encircles each of said shafts 19 and is interposed between the cover plate and the selector disk to normally hold the selector disks with their detents 23 engaged between the teeth of the pinions. When so positioned, as will normally be the case, rotation of the shafts by manipulation of the knobs 20 will cause the pinions 10 to rotate therewith.

The slide plate 12 is provided in the median line thereof with a pair of spaced upstanding locking elements 25 which, when the slide bar or plate 12 is in projected or locking position, will overlie the selector disks 22 to prevent the latter becoming disengaged from their respective pinions 10 and to insure interlocking of these parts together. This operation is clearly shown in Fig. 5. The locking elements 25 are so positioned, however, that when the plate 12 is in retracted or bolt-released position, they will be removed from above the selector disks 22 so that the latter may be disengaged from their underlying pinions 10 upon upward movement being applied to the shafts 19 against the tension of spring 24. This is clearly shown in Fig. 4 of the drawings.

Sliding movements of the slide plate 12 are governed by the knob 26 affixed to the upper end of shaft or post 27 secured to the plate 12 and passing through a slot 28 in the cover plate 9'.

From the foregoing, it will be seen that the combinations necessary for proper actuation of the lock may be set as desired with the assurance that this combination is impossible of being changed when the lock bolt is in locked or operative position. In the present instance, the stems or shafts 19 have been set so that the underlying pinions 10 will be positioned with their recesses 18 in lug receiving position when the pointers or indicators 21 are on the numerals 3—3 of the housing. As so positioned, the slide plate 10 may be freely reciprocated, either to locking or unlocking positions. This is shown in Figs. 4 and 5. With the slide plate moved forwardly or to projecting or locking position, rotary movement applied to either or both of the knobs 20 will move the recesses 18 out of longitudinal alignment with the lugs 17, whereupon any movement of the plate 12 rearwardly or to unlocking position will be resisted by engagement of either or both lugs 17 with the peripheries of the teeth 11 of the pinions 10. Movement of the slide plate 12, therefore, will be prevented until both shafts 19 have been rotated to such position as to dispose the recesses 18 in the pinions 10 in longitudinal and cooperative alignment with the lugs 17.

When it is desired to change the combination, the plate 12 is moved to retracted position with the lugs 17 engaged within the recesses 18 and the locking elements 25 moved rearwardly to the positions shown in Figs. 2 and 4. When so positioned, upward sliding movement applied to either or both of the shafts 19, against the tension of springs 24, will lift plates 22 sufficiently to withdraw detents 23 from engagement with the teeth 11 of the pinion 10. Rotary movement to the shaft when so elevated will move the detents 23 to different positions and release of the knobs 20 to the tension of springs 24 will force the disks 22 downwardly so that the detents 23 will engage between the new selected teeth of pin-

ion 10. The number of different combinations possible will be determined by the number of teeth in the pinions 10, and this number may be varied as desired.

In instances where a "push" action of the shaft 19 is desired for bringing about a combination change, the parts will be somewhat reversed as shown in Fig. 7. In this figure, the shaft 19 is mounted in the casing in reversed position, and the spring 24 is interposed between the disk 22 and the top plate 9' of the housing. The slide operating knob 26 is also shown in reversed position in order that a sliding movement of the plate 12 may be effected. In this modified form of the invention, the pointer or indicating elements 21 are omitted, and a pointer or indicator 21' is shown as forming a permanent part of the knob 20' of this modified construction.

From the foregoing it is apparent that I have provided a lock structure for controlling the sliding movement of a locking plate which embodies all the advantages of the structure shown in my former patent but in addition thereto simplifies the construction of the lock as well as its operation. The lock here disclosed embodies the simplified form of lock structure merely for controlling or governing the sliding movements of a plate. This plate may be utilized as a locking bolt for any type of closure to which it may be applied, or may be utilized for such purposes as are suggested in my former patent. The present illustration is of a lock showing a pair of operating shafts, but it will be understood that a single shaft may be used in a simpler form of lock, or additional shafts may be provided if desired.

I claim:

1. In a lock, a casing, a pinion rotatably mounted in said casing, a slide bar in said casing, 40 a lug on said bar projecting toward said pinion, said pinion having a recess in its periphery to receive said lug when said pinion is in a predetermined position, a shaft rotatable in said casing and concentric with said pinion, a disk secured to said shaft, a detent on said disk for locking engagement with a tooth of said pinion, and a spring yieldably holding said disk with its detent engaged with said pinion.

2. In a lock, a casing, a pinion rotatably mounted in said casing, a slide bar in said casing having an opening to receive said pinion, a lug on said bar, said pinion having a recess in its periphery adapted to receive said lug when said pinion is in a predetermined position, a shaft 55 rotatable in said casing and concentric with said pinion, a disk carried by said shaft, a detent on said disk for interlocking engagement with a tooth of said pinion, and a spring surrounding said shaft and yieldably maintaining said disk with its detent interlocked with a tooth of said pinion.

GEORGE T. HOSKING.
